UNITED STATES PATENT OFFICE.

CALEB C. DULA, OF YONKERS, NEW YORK.

DESIGN FOR A SMOKING IMPLEMENT.

47,687.

Specification for Design. Patented Aug. 10, 1915.

Application filed April 9, 1915. Serial No. 20,345. Term of patent 14 years.

To all whom it may concern:

Be it known that I, CALEB C. DULA, a citizen of the United States, residing at Yonkers, in the county of Westchester and State of New York, have invented a new, original, and ornamental Design for Smoking Implements, of which the following is a specification, reference being had to the accompanying drawing, forming a part thereof, wherein—

implement made in accordance with the invention. Fig. 2 is a bottom plan view; and Fig. 3 is a front elevation.

I claim:

The ornamental design for a smoking implement, as shown.

CALEB C. DULA.

Witnesses:

F. L. FULLER,
